CLAIM

The ornamental design for a computer, as shown and described.

DESCRIPTION

FIG. 1 is a front, perspective view of a computer showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is another rear perspective view thereof;

FIG. 10 is a front, perspective view of a second embodiment thereof;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a rear perspective view thereof; and,

FIG. 18 is another rear perspective view thereof.

The broken lines are environmental only and form no part of the claimed design.
